UNITED STATES PATENT OFFICE.

JOHN L. MOHUN, OF OMAHA, NEBRASKA.

LOCOMOTIVE.

Application filed March 1, 1926. Serial No. 91,380.

This invention relates to improvements in locomotives and particularly to locomotives of high capacity for heavy service conditions.

5 In railway practice, there is a constant tendency, in the interest of economy, toward increased length and tonnage of trains with the resulting demand for locomotives of increased capacity to meet these requirements 10 efficiently under all service conditions. To obtain the increased capacity of locomotives for this purpose necessarily involves increasing the size and weight of the locomotives correspondingly. There are necessarily 15 limitations to the height and width of locomotives on account of the restrictions due to road clearances. The permissible weight is also restricted on account of the limitations in the carrying capacity of the usual rails. 20 The weight of the locomotive must be distributed uniformly over the rails and for the heaviest rails now used the maximum permissible weight per axle of the locomotive ranges from 55,000 to approximately 25 65,000 lbs.

To obtain a thorough understanding of certain peculiar conditions which have been encountered in developing locomotives to keep pace with trains of constantly increasing length and tonnage, it is advisable to outline, in brief, the developments which have taken place in locomotives and the characteristics of locomotives having the greatest capacity and power consistent with economy prior to my invention as known to me.

As will be well known to those skilled in this art, the earlier types of freight locomotives included the mogul, the ten wheel and the consolidation types. Those used in passenger service were the 4-4-0 or American, the 4-6-0 or ten wheel type, and the 4-4-2 or the Atlantic type. Later came the Mallet articulated type with two high and two low pressure cylinders which was followed by the 4-6-2 or Pacific type and the Cole four cylinder compound locomotive. The weights and tractive powers of the consolidation were increased and the mikado or 2-8-2 also entered the field. The Mallet type was also further developed and the arrangement varied from the 0-6-6-0 type and the 2-8-8-0 type to the 2-10-10-2 type. All types increased in weight and power. Then followed the mountain or

4-8-2 type, and the Santa Fe or 2-10-2 type, the Virginian or 2-10-10-2 Mallet type. Other types involving long rigid wheel bases were the 4-8-2, 2-10-0 and the 2-10-2 types.

Even with the heavy rails now used permitting the maximum weight per axle of from 55,000 to 65,000 lbs., and the long rigid wheel bases of the types of locomotives last referred to, it appeared that the limit in weight and power for a two-cylinder simple locomotive had been reached.

With the heavy reciprocating and rotating weights of the modern locomotive, the hammer blow on the rail of the weight referred to, added to the driving wheel counterbalance to balance the reciprocating parts, has been a serious problem. It is therefore evident that the important problem in locomotive design is to increase the weight on the individual drivers, to increase the boiler efficiency and to reduce the counter balance for reciprocating parts.

In increasing the size and weight of two cylinder locomotives to meet the requirements for more power, the limit was reached on account of the restriction imposed by road clearances, thus limiting the size of the cylinders which can be used. In increasing the size of the cylinders, the piston thrusts also become exceptionally high, thereby placing the crank pin connections under excessive strain. In order to further increase the size of locomotives and avoid the difficulties pointed out, two additional cylinders were added, each pair of cylinders being associated with a separate articulated truck. The 0-6-6-0, 2-8-8-0, 2-10-10-2 hereinbefore referred to are of this type. The last-named construction has serious defects in that the arrangement of the second pair of cylinders rearwardly of the first pair requires complex steam and exhaust connections for these cylinders.

Recently the three-cylinder locomotive has been developed wherein the three cylinders are all placed at the forward end of the locomotive, the third cylinder being located midway between the two side cylinders. Although experiments were made years ago with locomotives of the three cylinder type, it is only in recent years that they have gone into successful service in the United States. By providing the third cylinder between the

other two cylinders, the total cylinder capacity of the three cylinder locomotive is greatly increased over the two cylinder type without interfering with road clearances. As 5 the three cylinders are placed so as to operate 120° apart, it is evident that the weight of the reciprocating parts is greatly reduced and the hammer blow is also minimized. The counter balancing problem is also different 10 than in the two cylinder type, whereby a great reduction in the weight of the rotating and reciprocating parts of each individual cylinder is had. With the increased number of exhaust impulses per revolution in 15 the locomotive of the three cylinder type, the draft on the fire is also much more steady, particularly at low speeds. Due to the more uniform turning movement of the parts, a greater tractive power per pound of weight 20 on the drivers is had. An outstanding advantage is in the ability to handle trains when once in motion at a shorter cut off than the two cylinder type. In the two cylinder type, the arrangement of the cranks is such 25 that the mean tractive effort will rise materially at one point in the revolution of the drivers and unless there is sufficient weight on the drivers the latter will slip. In the case of the three cylinder arrangement, with 30 the same cut-off and mean tractive effort, the increase will be materially less, requiring much less adhesive weight to prevent slipping than the corresponding two cylinder design.

35 It will thus be seen that the three cylinder locomotive has a very high starting torque uniformly applied, thus reducing the stress on the draft gears and other parts and also that when the train is once in motion, it may 40 be hauled at a much shorter cut-off than with the two-cylinder type.

On account of the counter-balanced condition of the three-cylinder locomotive and the more even distribution of the piston impulses, the average boiler pressure is maintained better under all service conditions.

The most successful locomotive of the heaviest three-cylinder type known to me prior to my invention comprised ten drivers, 50 arranged in pairs mounted on a rigid base, one pair of drivers having lateral motion. As the weight of the locomotive is distributed to the different drivers and the maximum permissible weight per axle is 55 approximately 65,000 pounds, the size and weight of the boiler and other parts of the ten-wheel three-cylinder type are necessarily limited.

Notwithstanding the advances that have 60 been made, the demand for higher capacity locomotives which will operate efficiently, and economically, has not been completely met.

One object of my invention is to provide a 65 locomotive of exceptionally high capacity

and efficiency without exceeding the permissible weight per driver axle, which is economical in operation and capable of moving heavy tonnage trains at high speed, thereby greatly reducing operating costs.

More specifically an object of my invention is to provide a locomotive of high capacity which will operate efficiently by an arrangement of cylinders all located at one end, associated with a rigid wheel base, 70 wherein the maximum number of drivers permissible with tracks of standard design and modern accepted weight are provided by permitting lateral movement of certain of the drivers.

Another object of my invention is to provide a single steam locomotive unit of increased power over existing locomotives of this type so designed as to provide greater boiler capacity per unit of traction than is 85 attained in the single unit locomotive now in use, which conforms to accepted practice and at the same time is within existing limits of roadway clearances and does not overstress the present standard roadway.

A still more specific object of the invention is to provide a locomotive of the type indicated having the cylinders at the front end thereof, provided with a rigid wheel base including twelve drivers arranged in pairs, 90 the front and rear pairs of which have lateral motion, thus permitting the locomotive to pass over relatively sharp curves in common use without undue strain on the roadway and locomotive.

Other objects and advantages of the invention will more fully and clearly appear from the description and claims hereinafter following.

In the drawings, forming a part of this 105 specification, Figure 1 is a side elevational view of a locomotive engine embodying my improvements. Figure 2 is a front end elevational view of the locomotive shown in Fig. 1. Fig. 3 is a plan view of the running 110 gear, partly broken away, showing the cylinders and wheel driving arrangement of the locomotive. Figure 4 is a detailed view of an equalizing mechanism provided for the leading truck, as shown in Figure 5. Figure 5 is a partial side elevational view showing my improvements applied to a locomotive with a two-wheel leading truck. Figures 6 and 7 show two diagrams respectively illustrating the tractive power curves and 115 the drawbar pull curves of my improved locomotive as compared with locomotives of certain well-known types. And Figure 8 is a longitudinal sectional view, broken away, 120 of the forward end of the locomotive illustrated in Figure 1.

In said drawings, A indicates the boiler of a locomotive, B the leading truck, C the running gear. As shown in the drawings, referring first to the embodiment of the in- 130

vention illustrated in Figures 1 to 3, inclusive, the locomotive is provided with three cylinders D—D—D. As shown, the cylinders comprise a pair arranged at opposite sides of the locomotive and a third cylinder disposed midway between the former in a slightly inclined position.

The wheel base of the locomotive has 12 drive wheels 10 mounted thereon. As shown, the drive wheels 10 are arranged in six pairs and are coupled together for movement in unison by the side rods 11. The front and rear pairs of drivers 10 are so arranged as to have a certain amount of lateral motion, lateral motion journal devices 12—12 being mounted on the truck frame, as most clearly shown in Figure 3. It will be evident that on account of the standard construction of curves of tracks now in general use, a locomotive having six pairs of drivers, none of which have lateral motion, could not be operated around the curved track sections, it being possible to accommodate only a maximum of four or five pairs of drivers which are held against lateral motion on standard curves. For this reason, I have provided the front and rear sets of drivers with lateral motion devices as hereinbefore pointed out. In Figures 1 and 2, I preferably provide an arrangement of drivers having the two center pairs blind, that is, not having flanges. In this manner, the operation of the locomotive around curves is still further facilitated. It is also feasible to provide the two center pairs of drivers with lateral motion journals to facilitate the taking of curves. It will be evident that although I have shown the two pairs of central drivers as blind, this is not absolutely necessary as the locomotive will operate properly around curves which are not of excessive curvature even if all of the drivers are provided with flanges, so long as the front and rear pairs of drivers have lateral motion. The main rod of the central cylinder is designated by 13, and as shown is preferably connected with a crank member 14 provided on the axle of the second pair of drivers. The other pair of cylinders is provided with the usual main driving rods 15 which are connected to the usual crank pins 16, the latter being preferably located on the third pair of drivers. The two outer cylinders D of the locomotive are located within the prescribed limits of the standard road clearances now in use, and it will therefore be evident that by providing the third cylinder located between the outer pair, the amount of power is greatly increased over that which it is possible to obtain in two cylinder locomotives conforming to the standard road clearance restrictions. It will be evident that inasmuch as the size of two cylinder locomotives is limited on account of the existing clear-

ance limitations, it is impossible to obtain adequate cylinder power in a two cylinder locomotive without exceeding these clearance limitations, and further as locomotives of the two cylinder types having two sets 70 of cylinders involve added expense and weight, with a consequent sacrifice of reduction in the boiler capacity, it will be evident that a great advantage is obtained by employing a single group of three 75 cylinders. The further advantage of my improved design is that the middle cylinder is connected to one pair of drivers and the other cylinders are connected to a different pair of drivers, the crank pins of the two 80 sets of drivers being so related as to operate approximately 120° apart. By this arrangement, maximum cylinder power within road clearance requirements is provided, less thrust is placed on each individual crank pin, and the arrangement of disposing the crank pins 120° apart produces a more even turning moment with less tendency of the drivers to slip than in the equivalent two-cylinder locomotive. A 90 lower adhesive factor is thus permitted.

In the embodiment of the invention illustrated in Figures 1 to 3, inclusive, the locomotive is shown as provided with a leading truck B having four wheels. This truck, as shown, is disposed under the middle cylinder D and provides for a satisfactory distribution of the weight of the locomotive between the drivers and the truck. However, by providing a suitable equalizing 100 means, as shown in Figure 4, a two wheeled truck of the type shown in Figure 5 may be employed, the drivers being moved forwardly near the cylinders and the middle cylinder given a slightly greater inclination to 105 the horizontal than in the first form referred to. The trailer truck, which is designated by E, in Figure 1 may have any number of wheels to suit the load carried on this truck. It will be understood that a truck 110 similar to the truck E is also employed in connection with the embodiment of the invention illustrated in Figure 5.

In addition to the advantages of my improved locomotive over the prior art hereinbefore pointed out, by providing the six pairs of drivers, two of which are laterals, an enormous increase in capacity over the ten wheel type of three cylinder locomotive heretofore in use is obtained. In addition 115 to this, the efficiency is also materially increased over the three cylinder type referred to. By providing the additional pair of drivers, the length of the boiler is materially increased, thereby also increasing the length of the flues of the boiler, the length of the fire box and consequently greatly increasing the heating surfaces provided. With modern standard rails of the heaviest 120 type now employed, the permissible weight 130

per axle of a locomotive, as hereinbefore pointed out, ranges from 55,000 to 65,000 pounds. In view of this, it will be evident that the added pair of drivers means a decided additional advantage in increased locomotive capacity. With my improved locomotive as hereinbefore described, a very efficient tractive effort is developed at low speeds and the maintenance of this tractive effort at high speeds is substantially uniform. Compared with the best type of Mallet engine now in use, of substantially the same tractive effort as my improved three-cylinder type at three to five miles per hour, my improved type of three-cylinder locomotive will haul approximately twice the tonnage of the Mallet at 35 miles per hour. In other words, a tractive effort of upwardly of 95,000 pounds within a speed range of five miles an hour, and of substantially 45,000 pounds at 35 miles an hour is obtained by my improved design. This is graphically illustrated in the diagrams shown in Figures 6 and 7. In Figure 6, the horizontal lines indicate the tractive power in pounds and the vertical lines the speed in miles per hour. In Figure 7, the drawbar pull in pounds is indicated by the horizontal lines, and the speed in miles per hour by the vertical lines. The tractive power curve of the Mallet locomotive referred to is indicated by the line $a-b$ in Figure 6, the tractive power curve of a similar Mallet locomotive having 63" drivers is indicated by the line $c-d$ in the same figure. The tractive power curve of my improved twelve driver, three-cylinder locomotive is indicated by the line $e-f$ in said figure, the curves representing the drawbar pull behind the tenders of the locomotives of these three types being indicated respectively by the lines $a'-b'$, $c'-d'$, and $e'-f'$ in Figure 7.

The maintenance of high tractive effort at high speeds in my improved locomotive is possible due to the fact that the weight of the running gear is relatively light, thus permitting the use of a boiler of ample steam capacity to maintain these requirements, and at the same time remaining within the driving wheel weight limitations. The inherent design of the Mallet engine referred to is such that it requires a relatively heavy running gear, including two sets of cylinders, pistons, valves, etc. The weight of these parts necessarily restricts the weight that may be provided in the boiler and consequently a boiler of ample steam capacity to maintain the high tractive effort at high speeds is not possible without exceeding the driving wheel weight limitations.

The advantage of my improved twelve driver type of locomotive over the best type of three-cylinder locomotive known to me prior to my invention, is graphically illus- trated by the diagrams in Figures 6 and 7. In these diagrams, the tractive power curve and the draw-bar pull curve of the prior three-cylinder type hereinbefore referred to are designated respectively by $g-h$ and $g'-h'$. The three-cylinder type of locomotive referred to is provided with ten drivers arranged in pairs. As hereinbefore pointed out, the advantages of my improved locomotive over this type are due to the added length of wheel base, and increased boiler capacity, together with greater efficiency due to the larger area of the heating surfaces. At the same time, all the inherent advantages of the three-cylinder type of locomotive are retained.

It will be evident further that by my improved high capacity locomotive, trains of heavy tonnage may be handled at higher speed than heretofore, at the same time increasing the efficiency and economy of the locomotive and greatly reducing operating costs.

While I have herein shown and described what I now consider the preferred manner of carrying out my invention, the same is merely illustrative, and I contemplate all changes and modifications that come within the scope of the claims appended hereto.

I claim:

1. In a single unit steam locomotive, operable on tracks of standard gauge and modern accepted weight, said locomotive including: front and rear pairs of drivers having lateral motion, and a series of pairs of intermediate drivers, said series comprising at least four pairs of drivers, all of said drivers operating as a single unit; a set of driving cylinders all located forwardly of the drivers and operatively connected thereto, one of said cylinders being disposed between the remaining cylinders and all of said cylinders being confined within the clearance limits of present practice; and a boiler and accessory devices supported on said drivers, said boiler and devices together being of a total weight proportionate to the standard total weight permitted on all of said pairs of drivers, said boiler being of a size to deliver steam to said cylinders in evenly sustained quantity throughout the range of speed of the locomotive.
2. In a locomotive operable on tracks of standard gauge and weight, the combination with a boiler including other adjuncts; of a series of pairs of drivers supporting said boiler, said series including four pairs of drivers held against substantial lateral motion and additional pairs of drivers having lateral motion, all of said pairs of drivers being operatively connected and operating as a single unit, said boiler being of a size and weight proportionate to the permissible standard carrying capacity of all of said parts of drivers combined; and at least three

driving cylinders all located forwardly of said drivers and operatively connected thereto.

3. In a locomotive operable on tracks of standard gauge and weight, the combination with six pairs of drivers, said drivers being interconnected and operating as a single unit and having provision as to lateral motion as to some thereof, whereby to permit the locomotive to pass over curved tracks conforming to standard practice; of a set of three driving cylinders for operating all of said drivers, all of said cylinders being located at one end of the locomotive and operatively connected to said drivers, said cylinders being confined within the clearance limits of present practice; and means supported by said drivers for supplying power to the cylinders including a boiler of a size and capacity to deliver ample steam to provide maximum tractive effort throughout the speed range of the locomotive, the total weight of said power means and cylinders being so proportioned as to not exceed the standard total carrying capacity for said drivers.

4. In a single unit steam locomotive operable on tracks of standard gauge and modern accepted weight, said locomotive including: six pairs of intercoupled drivers operating as a single unit and having provision as to lateral motion as to some thereof, whereby to permit the locomotive to pass over curved tracks conforming to present practice without excessive strain to the locomotive or roadway; a set of at least three driving cylinders all located forwardly of said drivers and operatively connected to the latter, said cylinders being confined within the clearance limits of present practice; and a boiler arranged to deliver steam to said cylinders in sustained quantity to provide for high tractive effort throughout the speed range of the locomotive.

5. In a single unit steam locomotive operable on tracks of standard gauge and modern accepted weight, said locomotive including: six pairs of inter-coupled drivers operating as a single unit and having provision as to lateral motion as to some thereof, whereby to permit the locomotive to pass over curved tracks conforming to present practice without excessive strain to the locomotive or roadway; a plurality of driving cylinders all located forwardly of said drivers, one of said cylinders being operatively connected to one pair of drivers and the remaining cylinders being operatively

connected to another pair of said drivers, said cylinders being confined within the clearance limits of present practice; and a boiler arranged to deliver steam to said cylinders in sustained quantity to provide for high tractive effort throughout the speed range of the locomotive.

6. A single unit steam locomotive operable on tracks of standard gauge and modern accepted weight, said locomotive including: six pairs of inter-coupled drivers operating as a single unit and having provision for lateral motion as to some thereof, the weight on said drivers being maintained under 60,000 pounds per pair of drivers; a set of at least three cylinders for operating all of said drivers, all of said cylinders being disposed forwardly of said drivers and operatively connected thereto, said cylinders being confined within the clearance limits of present practice; and a boiler of a capacity characterized by the fact that it generates and delivers steam to said cylinders in sufficient quantity to provide for a tractive effort, on a level, exceeding 95,000 pounds within a speed range of five to eight miles per hour, and substantially 45,000 pounds at 35 miles per hour.

7. A steam locomotive engine having in combination, three driving cylinders, six pairs of inter-coupled drivers operating as a single unit, and means for providing lateral motion to the front and rear drivers to permit the engine to round curves without undue strain on the engine or roadway.

8. A steam locomotive engine having, in combination, three driving cylinders, six pairs of inter-coupled drivers operating as a unit, and means for providing lateral motion for the front and rear drivers to permit the engine to round curves without undue strain on the engine or roadway, and power means including a boiler so proportioned and arranged as to give the engine a high tractive effort at high speeds.

9. A steam locomotive engine having, in combination, six pairs of intercoupled drivers operating as a single unit, three driving cylinders, one of which is connected to one pair of drivers, and two of which are connected to another pair of drivers, and a leading truck dividing with the drivers the weight of the engine.

In witness that I claim the foregoing I have hereunto subscribed my name this 26th day of February, 1926.

JOHN L. MOHUN.
